UNITED STATES PATENT OFFICE.

SAMUEL J. LORD, OF MANCHESTER, NEW HAMPSHIRE.

STREET-SIGN HOLDER.

1,117,509.

Specification of Letters Patent.

Patented Nov. 17, 1914.

Application filed November 18, 1913. Serial No. 801,631.

To all whom it may concern:

Be it known that I, SAMUEL J. LORD, a citizen of the United States, residing at Manchester, in the county of Hillsboro and 5 State of New Hampshire, have invented new and useful Improvements in Street-Sign Holders, of which the following is a specification.

The present invention has reference to 10 sign holders, and more particularly to that type or class of sign which is in the form of a flat plate or board of wood, metal or other suitable material and is commonly used for street-indicating and analogous purposes.

15 The invention comprehends certain hereinafter-described structural improvements which render the holder capable of being readily applied, with equal facility, to lamp and other posts or supports, and to house 20 corners, trees and the like, and of accommodating itself to any surface irregularities of or in such supports, and it proposes, further, an improved holder of the general character indicated which may be manufactured at a minimum cost, is extremely durable, and is designed to effectively and 25 removably support the sign in level position, without sagging.

An embodiment of the invention is illustrated in the accompanying drawing, 30 whereof;

Figure 1 is a perspective view of the improved holder, with its sign, attached to a post; Fig. 2 is an enlarged front elevation 35 of the holder; Fig. 3 is a side elevation thereof; Figs. 4 and 5 are transverse and longitudinal sections, taken respectively, upon lines 4—4 and 5—5 of Fig. 2; and Fig. 6 is a side elevation of the sign, showing its rounded rear corners.

Referring more particularly to said drawing, 7 indicates generally the improved holder, 8 the sign carried thereby, and 9 the support to which the said holder is attached. 45 The element last mentioned may be of any desired character, and is here shown as in the form of, or as constituted by, a post of conventional type. In this instance, however, the holder is fastened to metal bands 10 which encircle the post and are secured thereto, instead of directly to the support, as is the case where trees, wooden poles and the like are used for that purpose. The sign itself may likewise be of any desired form, 50 but is preferably constituted by an elongated

rectangular board or plate, made of wood, metal or some other suitable material.

The holder which embodies the most important features of the invention, consists, by preference, of upper and lower body or 60 base portions 11 and 12, and a central connecting portion or bridge 13. The width of this bridge is appreciably less than that of the end or base portions, but, on the other hand, it extends or projects forward a very 65 considerable distance from what may be regarded as the front face of the holder. The said bridge is disposed longitudinally of the holder, and has its end portions extending partly across the adjacent base portions 11 70 and 12, as best shown in Fig. 2, at which points it is strengthened by webs 14, 15 and 16, the two transverse webs 14 and 15 at each end of the holder being located close to the inner edge of the corresponding base 11 or 75 12 and extending from the side edges thereof to the side walls of the bridge, while the vertical or longitudinal web 16 at each end extends from the outer edge of the corresponding base to the adjacent end wall of the 80 bridge. All of the above-mentioned component parts of the holder are of integral construction, thereby reducing the cost of manufacture to a minimum, since the entire holder has, therefore, the form of a one-piece or 85 unitary casting which may be made in stock from a single mold.

To permit the attachment of the sign to the holder the latter has formed in it, during casting, a longitudinal slot 17 which opens through the opposite faces of the bridge portion 13, and, like said bridge, is extended at its ends across or into the base portions 11 and 12. This slot is designed 90 to receive the rear or inner end of the sign, so that it, and the bridge through which it is formed, may be said, therefore, to constitute a socket, the portions 11 and 12 being the bases of such socket, and it may 95 here be stated that the inner or rear face of the bridge, which forms the back of the socket, is cut away or thinned, as shown in Fig. 3, to increase the space between said face and the surface of the post or other support. The sign end is fixed in the said socket by means of screws or nails 18, which pass through perforations 19 in the side walls of the socket, and to further insure 100 the retention of said sign end in place, especially before the fastening devices are 105 110

driven through their holes in the socket, the inner walls of the latter are inclined, so as to exert a wedging or binding action upon the sign. Thus, as shown in Fig. 4, the 5 inner surfaces 20 of the two side walls have a slight inward convergence, and, similarly, the inner surfaces 21 of the two end walls, as depicted in Fig. 5. Moreover, to facilitate centering, the rear corners 22 of the 10 sign are rounded, as indicated in Fig. 6.

The holder itself is fastened to its support in like manner, by means of nails or screws 23, which are driven into said support through perforations 24 formed in the 15 two base portions 11 and 12. These portions are preferably provided upon their inner faces, adjacent the side edges thereof, with rearwardly-projecting feet 25 which are coextensive in length with said edges 20 and are formed, in turn, with sharp-pointed lugs or teeth 26, such teeth serving as an additional retaining means for the holder since they are forcibly driven against or 25 into the post or other support during the attachment of the holder thereto.

In use, the rear end of the sign proper is first driven into the socket in the holder, as will be understood, and the said holder is then applied to its support and held there- 30 against in any desired manner prior to being fastened thereto. During the time that the holder is being held against the support, the sign is adjusted in the aforesaid socket, the depth of the socket and the rounded 35 rear corners of the sign permitting the sign end to accommodate itself to any uneven- ness or surface irregularity of or in the support and also permitting the sign itself to be positioned at the proper angle to said 40 support, while the wedge action exerted by

the inclined inner walls of the socket prevents the sign from falling out of the socket at such time. When the adjustment of the sign has been completed, it is fastened in the socket, and the holder then set- 45 cured to the support, or this operation may be reversed and the attachment of the holder to the support effected prior to the nailing of the sign in its socket. In either instance, it will be apparent that both sides or faces 50 of the sign are equally available for street names or other matter of a like character which can be readily read therefrom.

The general advantages of the invention are believed to be apparent from the foregoing, and, in consequence, to require no further explanation.

What I claim is:—

1. As a new article of manufacture, a one-piece metal sign holder formed with a 60 socket for the reception of one end of the sign, said socket having rearwardly-converging inner walls adapted to exert a frictional clamping action on the sign end.

2. A one-piece, metal sign holder com- 65 prising spaced base portions and an elongated bridge connecting the same, said bridge being formed with a transverse socket for the reception of one end of the sign, the inner walls of which socket con- 70 verge rearwardly to exert a frictional clamping action on said sign end.

In testimony whereof I have hereunto set my hand in presence of two subscribing witnesses.

SAMUEL J. LORD.
